HAND-GUIDED MOTOR-DRIVEN BARK
REMOVING PLOWLester E. Phillips, Cazadero, Calif., assignor of
one-half to James C. Hamilton, Santa Rosa,
Calif.

Application November 13, 1951, Serial No. 255,975

7 Claims. (Cl. 144—208)

1

My present invention relates to log bark peeling and more in particular to a portable log bark peeler for use by lumbermen.

Heretofore, in the logging camps, log peeling has been a slow and laborious procedure. Large logs such as large redwood logs have a very thick bark which must be removed before sawing into logs and lumber to prevent damage to the large and very expensive saws used.

The conventional method of peeling such logs has been to chip or break the bark off with iron bars somewhat like crow-bars before the logs go to the mill for processing into lumber. This is a slow process and very tiresome work as these bars weigh in the neighborhood of fifteen pounds more or less. In the course of one day a workman lifts many thousands of pounds of weight.

My present invention not only eliminates the hard work involved in peeling logs but makes it possible for one man to accomplish this operation easily and in fact do more work in a given length of time than can be accomplished with a whole crew of men.

The principal object of my invention is to provide a portable power operated log peeler which is compact and simple in operation and constructed with a minimum of parts, which is held and controlled by the two hands of the operator when in operation, and which is provided with a plow member with traction wheels that may be raised or lowered at will without retracting or moving the plow member thus permitting the driving motor to increase its torque when slowed down by heavy duty.

Another object of the invention is to provide a freely pivoted plow member having a skirt with a lower curved edge which rides on the log but the point of which wedges between the bark and the wood surface of the log, the weight of the machine being carried on the wheels of the machine and the rear portion of the skirt of the plow substantially below the pivot point of the plow.

A still further object of the invention is to provide a lock between the plow and the body of the machine so that when desired a three-point contact on the log may be obtained between the two traction wheels and the contact edge of the plow.

Other objects and novel features comprising the construction and operation of my invention will be more apparent as the description of the same progresses.

Referring more in detail to the drawings illustrating the invention—

2

Fig. 1 is a plan view of the machine as viewed from the top, portions of the machine being broken out for convenience.

Fig. 2 is a side elevation of the machine. The opposite side is a duplicate except that it is other-hand-to.

Fig. 3 is a fragmentary side elevation similar to Fig. 1 but showing the plow portion freely pivoted and unlocked from the body portion.

Fig. 4 is a fragmentary cross-section taken on the line 4—4 of Fig. 2 portions of which are in elevation.

Fig. 5 is a cross-section taken on the line 5—5 of Fig. 1, the near traction wheel being removed and other portions broken away to better show the driving mechanism and a portion of the inside of the traction wheel on the far side.

Fig. 6 is a fragmentary cross-section taken on the line 6—6 of Fig. 5 particularly showing the far side pivot between the plow portion and the body of the machine.

Fig. 7 is a fragmentary cross-section taken on the line 7—7 of Fig. 5 showing the gear train back of the traction wheels.

Fig. 8 is a fragmentary plan view of the face of one of the traction wheels.

Fig. 9 is a vertical section and elevation taken on the joint line of the split casing of the body portion and shows a modified form of motive power, the motor of which is shown in elevation.

Fig. 10 is a fragmentary plan view taken on the angle indicated by the arrow A of Fig. 9 and showing the operating valve.

Fig. 11 is a fragmentary cross-section taken on the line 11—11 of Fig. 9 and showing the arrangement of the motor.

Referring more in detail to the drawings, 10 and 11 indicate the far and near halves of the split casing comprising the heretofore referred to body portion. Each of these casings are provided with handle portions 10a and 11a having electrical control switches 10b and 11b.

Figs. 1 to 8 inclusive show a casing adapted for an electric motor drive. Figs. 9, 10 and 11 show a casing adapted for a compressed air motor, both types of machines are alike except for the substitution of air control valve shown in Fig. 10 and the internally mounted compressed air motor. In either case the motor is provided with a transversely located drive shaft. For the sake of simplicity both the shaft 12 which is an armature shaft shown in Figs. 1 to 8 inclusive and the shaft 12a of the compressed air motor shown in 9 and 11 are given the similar

numerals. The structure set forth in Figs. 1 to 8 inclusive will first be described.

On the front of the casings 10 and 11 is pivoted a plow member 13 having a penetration edge 14 extending across the entire width of the plow. The plow 13 is pivoted on the bolts 15 which are fixed in casings 10 and 11. The casings 10 and 11 are open on the major portion of the bottom side. Recessed areas 16 are provided in the sides of casings 10 and 11, the inner walls 17 of the recessed areas being provided in their central portions with bearing studs 18 on which are journaled the traction wheels 19 and 20. The traction wheels 19 and 20 are held on the studs 18 by the screws 18a. The traction wheel 19 is on the far side of the machine in the casing 10. In the lower portion of each recess 16 is a dust guard 21, the lower edge of which is radially aligned with the inner side of the adjacent wheel 19 or 20, see Fig. 4. This guard is for the purpose of preventing chips of bark etc., from jumping up into the geared mechanism. The wheels 19 and 20 freely turn on the studs 18. On the recess wall 17 is a pinion gear 22 which is keyed to the motor shaft 12. A stud 23a is mounted in the wall 17 and forms a journal for gears 23 and 24, the gear 23 meshing with the pinion gear 22. The gear 24 is fixed to the gear 23 and meshes with a gear 25 fixed to a pinion gear 26. Gears 25 and 26 are journaled on a stud 27 mounted in the wall 17. The wheels 19 and 20 are hollow and are provided on their inner rims with internal gear teeth 28. When the traction wheels 19 and 20 are mounted on the studs 18, the pinions 26 engage with the internal gear teeth 28 of the wheels. 29 indicates spurs located on the outer face of the traction wheels. Within the casings 10 and 11 is mounted, in any suitable manner, an electric motor, the numeral 30 (see Fig. 5) indicating the armature within which is mounted the armature shaft 12. It will thus be seen that when the motor armature rotates in a counterclockwise direction, the wheels 19 and 20 also rotate in the same direction and move the machine forward.

On each side of the machine on the casings 10 and 11 is located a slide member 31 which has teeth 34 and which is extended and retracted by means of toggle levers 32, the slide member 31 sliding in or out on a center line passing through the axis of the studs 15 on which the plow member 13 is pivoted. Adjacent the teeth 34 is a segmental row of gear teeth 35 cut in lower edge portions of a skirt 13a of the plow 13. When it is desired to lock the plow 13 to the casings 10 and 11 the slides 31 are pushed ahead, thus engaging the teeth 34 and 35. In this position the plow 13 is locked against pivot movement on the casings 10 and 11. When the slide is retracted, as in Fig. 3, the plow 13 is free to pivot on the studs 15.

Fig. 2 shows the machine in operation on the log 40. 41 indicates the bark of the log being lifted by the plow 13. When in operation, the plow 13 may be controlled vertically by the operator's hand grips 10a and 11a by holding the wrist stiff and leaning forward or backward. The same control is present when the plow is free, as in Fig. 3. Since by rocking the casing on the wheels 19 and 20, the angle, between the plow edge 14, the pivot 15, and the stud 18 on which the wheels are journaled, may be varied in such a manner that the plow edge 14 may be forced against the wood of the log. The bark 41 of the log exerts downward pressure on the

pointed end of the plow forcing it against the log 40. The plow is interchangeable with other plows of sharper or duller edges or of different frontal curves. In logs having very thick bark the leading edge 14 of the plow will follow the cleavage line between the bark and log with the plow freely pivoted on the casings. In the case of thinner bark the plow may be locked at any desired angle and pressure applied by forwardly rocking the handles 10a and 11a.

Another feature of the machine is that, with the plow either locked to the casing or unlocked, the wheels may be lifted from engagement with the log by using the pivot 15 as a fulcrum point and pivoting the body of the machine upwardly, thereby throwing the wheels out of engagement with the log without removing the plow and thereby permitting the motor to speed up, and then suddenly engaging the wheels with the log, so that the plow will thrust forward and thus break down resistance to its movement. The electric motor of the machine is controlled by switches 10b and 11b. One switch may be an off and on switch and the other a reverse switch. Electric power is led to the machine by means of a cable 59 connected with any suitable portable electric generator.

In Figs. 9, 10 and 11, the machine is motivated by compressed air. The only differences in this modification involve slight changes in casing structure to permit the substitution of an air valve and conduit for an electric switch and cable, and suitable changes in internal construction to permit the substitution of an air motor for the electric motor.

In Fig. 10 the drive shaft 12a which engages the drive gears is located in the same position as in the electric driven machine. A rotor 60 is keyed to the shaft 12a. A rotor chamber 61 is formed one-half on one casing and one-half on the other casing as indicated at 62 and 63. The rotor periphery is provided with transverse air receiving slots 64 which move past an air inlet passage 65, half of which is formed in one casing and the other half, in the other casing. The rotor slots 64 together with the side walls of the rotor chamber provide pockets 66 into which the air is projected against the vane portions 67 of the rotor, thus driving the rotor ahead.

The casings 62 and 63 differ over the casings 10 and 11 only in that the internal mountings of the casings 62 and 63 provide the rotor chamber etc., for the air operated motor while in the electric driven type suitable mountings would be furnished for the electric motor stator and windings etc., any suitable mounting arrangement being used but not of importance in the present application.

Casings 62 and 63 provide bosses 70 through which the air inlet passage 65 communicates with an air hose line 71. Compressed air is furnished from any suitable source such as a portable air compressor of the gasoline driven type which can be moved about on a suitable automobile truck in the same manner that a portable electric generator is utilized in the electric type machine.

An air valve control lever 75 is fulcrumed at 76 on the bosses 70. The operating end 77 of the lever 75 extends transversely of the casing 62 to a point close to the operating handle 10a and is depressed by the thumb of the operator's right hand. A valve stem 80 is located below the fulcrum end of the lever 75. A compression spring 85 normally holds the lever up as shown. A stop 75 member 86 engageable against the offset portion

87 of the bosses 70 prevents the lever 75 and valve stem 80 from rising more than is required for the closing of the valve. Depressing the valve stem 80 opens the valve, and admits compressed air to the rotor, the amount of pressure against the rotor vanes 67 being proportional to the valve opening and the pressure source.

The rest of the machine shown in Fig. 9 corresponds to the machine shown in Figs. 1 to 8 inclusive.

Any other traction surface for the wheels 19 and 20, such as round spikes, may be used if desired.

While the machine is shown travelling around the diameter of a log it is not necessarily so limited in use. It is capable (especially on large logs) of operating longitudinally of the log or around the log in a spiral track, depending on the size of the log with respect to the width of the plow 13 etc.

While I have shown the present machine somewhat in detail yet it is to be understood that I may vary the shape and proportions and use equivalent structure well within the spirit of the appended claims.

Having thus described my invention what I claim as new, is:

1. A log peeling machine comprising a rear casing, a power drive shaft mounted within and transversely of said casing, traction wheels journaled on said casing and driven by said drive shaft, said wheels being recessed in outer sides of said casing, and means for engaging said shaft with said wheels, operating handles located on an upper rear portion of said casing, a bark-removing plow positioned in front of said casing and provided with side skirts and with a concave front wall having a sharp lower edge, said side skirts being pivoted to the front portion of said casing, and means for driving said shaft.

2. A log peeling machine comprising a casing, a power drive shaft mounted within and transversely of said casing, traction wheels journaled on said casing and driven by said shaft, operating handles located on an upper rear portion of said casing, a bark-removing plow positioned in front of said casing, said plow having a sharp forward lower edge, a concave front wall, and rearwardly extending side skirts having lower edge portions curving rearwardly and upwardly, and means pivotally connecting said side skirts to said casing, whereby said casing can be lifted

out of contact with a log while said plow remains in bark-removing position.

3. A log peeling machine as set forth in claim 2, the lower rear edges of said skirts being provided with segmental gear teeth engageable with gear teeth formed on a slide member located on said casing.

4. A log peeling machine comprising a casing having recesses formed in its sidewalls, a compressed air motor located in said casing, a drive shaft mounted within said motor and transversely of said casing, traction wheels journaled on said casing and driven by said shaft through a gear train, said traction wheels being located in said recesses and protruding beyond lower portions of said casing, a bark-removing plow having side skirts pivoted to front portions of said casing and having a concave front wall terminating at its lower edge in a knife-like blade, 20 said front wall merging along its upper edge into a top wall connecting said side skirts.

5. A log peeling machine as set forth in claim 4 and locking members provided on the sides of said casing, said locking members being engageable with locking means on the skirts of said plow member.

6. A log peeling machine comprising a motor casing, a motor driven shaft mounted within and transversely of said machine, traction wheels 30 journaled on said casing and driven by said shaft, operating hand grips located on said casing and having motor control means adjacent to said handles, a plow member having a concave front wall and having side skirts, said plow skirts being 35 pivoted to said casing, said front wall having a knife-like lower edge, and means for supplying motive power to said motor.

7. A log peeling machine as set forth in claim 6, and locking means provided between said casing 40 and said plow member to prevent relative pivotal movement of said casing and plow member.

LESTER E. PHILLIPS.
